UNITED STATES PATENT OFFICE.

WILLIAM E. NICKERSON, OF CAMBRIDGE, MASSACHUSETTS.

ELECTRIC CONTROLLING DEVICE FOR ELEVATOR-CARRIAGES.

SPECIFICATION forming part of Letters Patent No. 403,439, dated May 14, 1889.

Application filed March 5, 1889. Serial No. 301,873. (No model.)

To all whom it may concern:

Be it known that I, WILLIAM EMERY NICKERSON, of Cambridge, in the county of Middlesex and State of Massachusetts, have invented certain new and useful Improvements in Electric Controlling Devices for Elevator-Carriages, of which the following, taken in connection with the accompanying drawings, is a specification.

My invention consists in making an electric device by which an electric motor or motors which control the hoisting-engine of an elevator may be caused to operate, said device embodying a set of fixed cams in the elevator-well adapted to automatically change the position of electrode terminals, so that they may come in contact with sets of circuit-closing terminals arranged on movable switch-blocks. The two sets of terminals—namely, those operated by the fixed cams in the elevator-well and those on the movable switch-blocks—are adapted to coact with each other in such a manner that the attendant, regardless of the position of the carriage, can so set the switch-blocks that the carriage will stop automatically at any floor.

I have illustrated my invention in the accompanying drawings, in which—

Figure 1 is a vertical section showing parts of an elevator-well, the carriage, and a diagrammatic illustration of the electric device. Figs. 2, 3, 4, and 5 illustrate the position and arrangement of the fixed cams as modified. Fig. 6 is a cross-vertical section through the switch-box located in the elevator-carriage, showing the interior arrangements. Fig. 7 is a horizontal section through the switch-box, showing the interior arrangements. Figs. 8 and 9 are diagrams for illustrating the action of the switch-blocks and cams. Figs. 10 and 11 show a modified form of my switch-box.

In the drawings, Fig. 1, I have shown an elevator-carriage, B, and its hoisting-rope C, the well-room being indicated by A and the various floors by A' A² A³ A⁴.

I have within the elevator-well two sets of fixed cam-pieces, D D' D² and E E' E², made, as shown, of different degrees of projection, the use of which will be explained below. Within the elevator-carriage I have a switch-box, H, the interior parts of which are shown in Figs. 6, 7, and 8.

M' M, Fig. 1, represent an electric device connected to the switch-box H within the carriage and adapted to set in motion that part 55 of the controlling mechanism of the hoisting-engine that causes the ascent of the elevator-carriage, and P' P represent an electric device to be used for directing the descent of the elevator-carriage. 60

I will now describe my switch-box and its contacts and their operation in connection with the fixed cams D D' D² and E E' E².

L and N, Fig. 7, represent bent levers pivoted, respectively, at L' and N', and having 65 stops L⁴ N⁴ and retractor-springs L³ N³. The outer ends, N⁵ L⁵, of the levers N and L project beyond the walls of the elevator-carriage, so that they may be acted upon by the cam-pieces D D' D² and E E' E². The inner ends, 70 N² L², of the levers N and L, when not acted upon by the cam-pieces nor by the moving switch-blocks D³ E³, Figs. 6 and 7, remain in the position shown in full lines in Fig. 7—that is, the springs N³ L³ hold the levers N 75 and L against their respective rests N⁴ L⁴, thus causing the ends N² L² to rest in the position shown.

The switch-blocks D³ and E³ are mounted rigidly on a common shaft, K, which has housings K' K', as shown in Figs. 6 and 7. The switch-blocks D³ and E³ are so set on the shaft K that the greater depressions, R, Fig. 6, of each coincide, as shown; but the inclines and lands d d' d² of D³ are on one side of the depression R, while the inclines and lands e e' e² of E³ are on the opposite side. From R, the point of lowest depression, the switch-block D³ is cut away, as indicated by d⁴ d⁵, Fig. 6, and from R, the point of lowest depression, 90 the switch-block E³ is cut away, as indicated by dotted lines e⁴ e⁵, Fig. 6. Each of the switch-blocks D³ and E³ has a series of inclines and lands. Those on the block D³ are indicated by d d' d² in Fig. 6, (see also diagram, Fig. 8,) and those on the switch-block E³ are indicated by e e' e², Fig. 6. The switch-blocks D³ and E³ are turned by means of the handle K², which is attached to the shaft K, as shown in Figs. 6 and 7. 95

The electrical connections within the switch-box H are as follows: The electrode T, common to both electric devices M' M and P' P, is connected to the switch-blocks D³ E³ through 100

the shaft K at *t*, Fig. 7. The electrode M² from the electric device M M' is connected at *m* to the lever N, and the electrode P² from the electric device P P' is connected at *p* to the lever L. (See Fig. 7.)

The cam-pieces D D' D² and E E' E² may or may not act on their respective levers N and L when the elevator-carriage is in motion, their action depending upon the position of the levers, and their position in turn depends upon the position of the switch-blocks D³ and E³, as I will now explain. When both levers are in the position indicated by full lines in Fig. 7, then the elevator-carriage is still, and of course no action can take place; but if the switch-blocks D³ and E³ are turned so that one of the lands, *d*, for instance, has passed under the end N² of the lever N, then the carriage in its upward motion would bring the lever N in contact with the fixed cam D², (see Fig. 1, and also the diagram, Fig. 9,) in which case the lever N will be thrown in the direction of the arrow S, Fig. 7, so as to occupy the place indicated by *n*³, Fig. 9, and its end N² would be moved away from the land *d*—that is, out of electrical contact with it—and the lever L (the inner end, L², of which being moved on the curve of lowest depression *e*⁴ *e*⁵, Fig. 6) will be moved by the cam-piece E', Fig. 1; but the movement of this lever has no effect whatever while the elevator-carriage is in its ascent. By turning the switch-block D³ so that the next land, *d'*, comes under the end N² of the lever N, then the lever will be moved so that its outer end will not touch—that is, be effected by the cam-piece D². Then it (the outer end of the lever) will come in contact with the cam-piece D' in the ascent of the carriage and will be thrown out, so as to break the contact between the inner end N² of the lever and the land *d'*. The same relative coaction of parts will take place at each successive replacement of the lands *d* *d'* *d*², and the contacts will be made and broken between the end N² of the lever N and the lands *d* *d'* *d*², and the same is true when the elevator-carriage is descending, except that the movements and contacts relate to the lever L, switch-block E³, and cam-pieces E E' E².

In the ascent of the carriage the lever L moves, but has no effect, as its switch-block E³ is in such a position that the curve of lowest depression is opposite the inner end and it can have no electrical contact. In the descent of the carriage the lever N is not affected.

The operation of my device is as follows: If we suppose the carriage to be at the bottom 60 of the well or first floor, and that it is desired to have the carriage ascend to the second floor, then the attendant will move the handle K², Fig. 6, down to the point marked 2. That act will cause the land *d* to come to a 65 position opposite to and in contact with the end N² of the lever N, thus making an elec-

trical connection between the electrodes T and M² and completing the circuit for the electric device M' M, thus setting the carriage in motion upward. This motion will continue until the carriage reaches the second floor. Then the end N⁵ of the lever N will come in contact with the cam-piece D², Figs. 1 and 9, and the cam-piece D² will throw the end N⁵ of the lever N in the direction of the arrow S, Fig. 7, so that it will occupy the position indicated by dotted lines *n*³, Fig. 9. This movement of the lever N will cause its end N² to break its contact with the land *d*, and thus break the circuit between T and M² of the electric device M' M and stop the carriage. If the carriage is at the bottom and it is desired to go to the top without stopping at any intermediate floor, then the attendant sets the hand K² to the point marked 4 on the dial-plate K³, Fig. 6. This action will set the switch-block D³ so far down as to cause the end N² of the lever N to occupy the position shown by *n*², Fig. 8, and of necessity cause the end N⁵ of the lever N to move in the direction of the arrow S and to occupy the position indicated by dotted lines in Fig. 6. In this position the end N² will be in contact with the switch-block D³ and the circuit of the electric device M M' closed, causing the elevator-carriage to ascend; and as the end N⁵ of the lever will be in the position indicated by the dotted lines in Fig. 7—that is, so far away from the line of the cam-pieces D and D' that it will not come in contact with them—it (the lever) will not be moved until the end N⁵ comes in contact with the cam-piece D of the top floor. Then the end N⁵ is thrown still farther over in the direction of the arrow S, so as to throw the end N² out of contact with the switch-block D, and thus break the circuit of the electric device M' M and stop the carriage.

To cause the carriage when at any position to stop at any floor, the attendant has simply to move the lever K² up or down to the number on the dial K³ designating the floor to which he wishes to stop, (in going up the lever should be moved to a + number and in going down to a -- number,) and, as has been explained, the switch-contact will be broken at the designated floor and then stop the carriage.

In the drawings, Figs. 2, 3, 4, 5, 10, and 11, I have shown a modification of the lever arrangement in my switch-box. In the modification I have substituted the lever Y and the sliding rod Y' for the bent lever N and the lever W and its sliding rod W' for the bent lever L, the other parts in the switch-box being the same. It will be observed that in using the push-rods Y' and W' instead of the levers N and L it will be necessary to rearrange the cam-pieces in the elevator-well room. I have shown in Figs. 2, 3, 4, and 5 the modified cam-pieces in cross-section, their distance of projection being measured from

the face of the wall, since they push the rods Y' W' in a line perpendicular to the walls of the elevator-well and of the carriage.

The leading feature of my device consists of series of cam-pieces fixed in relation to the elevator-well and arranged to move electric switch-levers projecting from the elevator-carriage, the amount of movement of the levers—that is, the projection of the cam-pieces—being different for each floor, so that if contact-points (for the switch-lever to touch) are made movable within the carriage and within the control of the attendant then the movement of the levers caused by the cam-pieces automatically breaks the circuit and stops the carriage.

I claim—

1. In an electrically-controlled elevator, the combination of series of fixed cam-pieces of

varying projections with electrical contact 20 making and breaking levers adapted to be set by movable switch-blocks for automatic action, and movable switch-blocks, substantially as and for the purpose set forth.

2. In an electrically-controlled elevator, the 25 combination of the cam-pieces D D' D² and E E' E² and the levers N and L with the switch-blocks D³ and E³, substantially as and for the purpose set forth.

In testimony whereof I have signed my name 30 to this specification, in the presence of two subscribing witnesses, on this 2d day of March, A. D. 1889.

WILLIAM E. NICKERSON.
